CLAIM

I claim the ornamental design for a cutter, as shown and described.

DESCRIPTION

FIG. 1 is a top, front, and right perspective view of a cutter showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a top, rear and left perspective view thereof; and, FIG. 9 is a top, front, and right perspective view thereof, wherein the components of the cutter are in an alternate position.

The broken lines in the drawings illustrate portions of the cutter which form no part of the claimed design.

1 Claim, 7 Drawing Sheets
